PHOTOGRAPHIC TYPE-COMPOSING

BACKGROUND AND BRIEF DESCRIPTION OF THE INVENTION

This invention pertains to a high-speed straight matter photocomposing machine for projecting proportionately-spaced character images on an image-receiving surface such as film of photosensitive paper, in order to form lines of print of graphic arts quality at computer print-out speeds.

High-speed non-impact computer print-out machines are known. Similarly, photocomposing machines which print proportionately-spaced lines of graphic arts quality have been in commercial use for many years. However, there does not exist a non-impact printing machine which combines quality typography with computer print-out speed at moderate prices. For purposes of this discussion, "computer print-out speed" is defined as composing speeds in excess of 1,000 lines per minute, wherein each line contains a minimum of 64 alphanumeric characters.

The present invention retains the known non-impact technology of a rapidly rotating character matrix drum, but adds the innovative concepts of special character orientation, as well as "flash delay" combined with "area overlap." Specifically, an array of characters are positioned on a rotatable drum in a plurality of rows and columns. The characters are oriented such that they pass through an arcuate projection zone with their leading edges parallel to the drum axis, rather than perpendicular thereto, as in the prior art. This enables each of the characters to be illuminated at any one of a plurality of locations within the projection zone as they pass therethrough, thereby effectively sweeping a latent image of each character across a portion of an image-receiving surface such as a film or photosensitive paper. After each of the selectively illuminated character images has been reoriented by passing through an associated respective optical deflector (such as a dove prism), the images are projected or focused along a common base line on the film in proportionately-spaced relation to one another. As is apparent in FIG. 2 of the drawings, the character image displacement areas on the film which are formed by the associated image deflectors overlap those of the deflectors immediately contiguous thereto, so that a series of character images of narrower or wider than average width may be even more precisely positioned relative to one another. Therefore, the present invention enables a full line of graphic arts quality to be printed for each revolution of the drum. Precise proportional character spacing is ensured by the employment of "flash delay" combined with "area overlap," while computer print-out speed is achieved by composing a full line for each drum revolution.

While a drum is preferred, the character-carrier may comprise an analogous arrangement such as an endless belt. Similarly, the use of a plurality of flash lamps as the source of illumination may be modified by the employment of a "thin" cathode ray tube or laser light source, instead of the lamps.

The present invention will be more fully described in the detailed description which follows, in which:

FIG. 1 depicts the preferred embodiment of the matrix or character-carrier of the machine;

FIG. 2 represents a part-sectional, broken plan view of the machine;

FIG. 3 is a cross-sectional end view of the machine of FIG. 2;

FIG. 4 is a schematic representation of the manner in which a character image is swept across a portion of the film after having been reoriented by the dove prism; and

FIG. 5 is a perspective view of an alternative embodiment in which the character-carrier is upright relative to the moving film.

DETAILED DESCRIPTION OF THE INVENTION

Referring to FIGS. 1 and 2 of the drawings, characters, transparent on opaque background are located on movable matrix drum 4. The characters are arranged in parallel rows or

- circles 6, 7 . . . 13 etc. as shown. This arrangement results in a plurality of columns as shown in FIG. 1. There are approximately as many circles as the maximum number of characters of average width that can be accommodated in the longest line which is to be composed. The characters are spaced around the drum so that there cannot be more than one character of each circle at a given time within an angle 2, hereafter referred to as the "arcuate projection zone." The matrix drum is adapted to continuously rotate, and any character located in the arcuate projection zone 88-89-90-91 representing the drum slice limited at both ends by the projection arc, as shown, can be projected onto a light sensitive surface 36 by a flash of very short duration all of which is controlled by control means 12. The timing of the projection flash is determined by the position of the character to be projected and the location of said character in the line to be composed, as explained in U.S. Pat. Nos. 3,291,015, and 3,416,420, and copending U.S. applications Ser. No. 690,720 filed Dec. 13, 1967 and Ser. No. 827,128 filed May 21, 1969.
- Each character is accurately located on the matrix drum in relation to the others as well as to a "zero" line or reference point 88-90. This accurate positioning is accomplished by the use of a reference point for each character as explained in the above-mentioned patents and applications. As shown in FIG. 1, characters of each row are preferably positioned on the drum so that their base line is concentric with the drum axis, the base line being shown at 6, 7 etc.
- Various sectional views of the machine are shown in FIGS. 2 and 3 of the drawings. Matrix drum 4 is shown as an assembly consisting of the character area 40 and a hollow hub 18 which is supported by ball bearings 20. A fixed holder 16 secured to the base of the machine supports the stationary flashing assembly which is located inside the drum. This assembly comprises a plurality of flash units 14-1, 14-2, etc., (one for each character circle or row) condensing lenses (or equivalent optical system) generally designated at 22, and light baffles 24. The purpose of baffles 24 is to avoid "light cross-talk" (light overlap) by confining the light emitted by a given flash unit to the portion of the arcuate projection zone assigned to this unit and its associated character row or circle (such a zone is shown at 92 in FIG. 1). Similar light baffles 26 are located on the outside of the drum 4 in order to channel the light rays emerging from a desired character to the projection system associated with the row of the character. As discussed previously, the flash lamps may be replaced by a "thin" CRT or laser light source, if desired. In this case, the coherent light of a laser source would obviate the need for baffles.
- A typical optical system unit comprises an image-reorienting means such as an image rotating deflector, schematically shown at 30-1, 30-2, etc., and a projection lens 32-1, 32-2, etc. In the example shown, the deflecting means is a dove prism. The position of the prism in the figures is intended to be illustrative only. The projection units are secured in a longitudinal plate 34 attached to the frame of the machine. The light emerging from the projection lenses 32 impinges upon a photosensitive surface, shown in the form of a film or photosensitive paper 36.
- It is well known that certain prisms or other deflector units can rotate an image. The most commonly used deflector for obtaining image rotation is the dove prism. The operation of the machine is illustrated schematically in FIG. 4. In this figure, the arcuate projection zone 92 of FIG. 1 is represented by a plane 54. Line 52 of plane 54 represents either the base line of a character or the partial trace left on the plane by the displacement of a point of a character (for example, the letter "R") as it moves from position 52a to position 52b. Point 50 is 65 the equivalent of a dove prism turned around its long axis to rotate light rays by 90°. Line-object 52 is projected as an image 55 on plane 58 representing the film. Now it can be seen that, by flashing character R at different times as it passes through the arcuate projection zone represented by plane 54, it is possible to selectively position the image of the character

at any one of a plurality of locations along its base line on the film. In other words, a latent image of each character is swept across a portion of the film, and at the proper moment the character is illuminated, which results in an actual character image proportionately spaced from the other images in accordance with their respective widths. Of course, the amount of displacement of a character along the line to be composed depends on the dimensions or extent of the arcuate projection zone. 5

The area or latitude of displacement of a character represented by line 55 in FIG. 4, is also shown at 94-96 in FIG. 2. As shown, displacement areas or character image areas preferably overlap from character row to character row in order to leave more latitude in positioning a succession of characters which may be either narrower or wider than average. In unusual cases, it will be necessary for the drum to rotate two or more turns to produce a full line of composition. However, in most cases, one line of proportionately spaced characters will be obtained for each drum revolution. Thus, a drum rotating at a speed of 50 rps could produce up to 50 lines of composition per second, excluding the displacement time of the film for line spacing; line spacing time could be obviated by continuously displacing the film, as is well known in the art. 10

In the arrangement of FIG. 5, a simple lens 100 is used to project any character of the arcuate projection zone 88-89-9 0-91 of FIG. 1. This is achieved by positioning the characters on the drum as shown, and by storing a full page of type at a time. Characters of different lines are projected as they pass through the projection zone. It is understood, of course, that the arrangement of FIG. 5 also projects proportionately-spaced characters onto the image-receiving surface, thus composing lines of graphic arts quality. The film is also moved by conventional motor means in the direction of the lines of composition in order to produce proportionately-spaced lines of extended length, thereby composing a full page at a time. 15

The foregoing description is intended to be illustrative only. Various changes or modifications in the disclosed embodiments may occur to those skilled in the art. It is understood, therefore, that all such modifications which would be apparent to one skilled in the art are included within the scope of the present invention. 20

What is claimed is:

1. A photographic type composing machine comprising: a movable character-carrier having an array of characters arranged in columns and rows thereon, said carrier adapted to be moved such that each of said character columns passes successively and repetitively through a projection zone associated with said carrier, means for illuminating at least one of said characters as each of said respective columns passes through said projection zone, 25

5

a surface for receiving images of illuminated characters projected from said zone, optical means for focusing images projected from said zone onto said image-receiving surface, and control means to vary the time at which said illuminating means is energized, such that any character in a given column may be illuminated at any one of a plurality of locations within the zone as said column passes therethrough, whereby a latent image of each of said characters sweeps across a portion of said image-receiving surface, in order to form lines of composition thereon in which the character images are proportionately spaced from one another in accordance with their respective widths. 10

2. The machine of claim 1 in which: said characters pass through said zone in a first direction, and

20 said image-receiving surface is oriented such that lines of composition will be formed thereon in a second direction, said machine including means for reorienting the images of characters projected from said zone such that said images are focused on said surface along a common base line in said second direction.

3. The machine of claim 2 in which said image-reorienting 25 means comprises a plurality of optical deflectors positioned so as to rotate the projected character images through a predetermined angle relative to said zone as said characters sweep therethrough, the degree of image rotation being sufficient to align said character images along a common base line which is perpendicular to the direction of motion of said carrier. 30

4. The machine of claim 3 wherein each of said deflectors 35 comprises a dove prism and an associated projection lens, and wherein each character has a corresponding deflector associated therewith during the passage of said character through said projection zone.

5. The machine of claim 4 wherein: said carrier comprises a rotatable drum, said projection zone is arcuate, and is of sufficient dimensions to include not more than one character column at any given time, and said deflectors are positioned adjacent to one another such that a character image area on the image-receiving surface for a given deflector partially overlaps those of the deflectors immediately contiguous thereto, in order to properly position thereon a series of character images which may be narrower or wider than average. 40

6. The machine of claim 1 including means for moving said image-receiving surface in the direction of said lines to be composed, in order to form proportionately-spaced lines of composition of extended length. 45
